UNITED STATES PATENT OFFICE

THEODORE LIND, OF TAYLORVILLE, ILLINOIS.

FOOT-CONTROLLED ACCELERATOR.

1,301,580.

Specification of Letters Patent.

Patented Apr. 22, 1919.

Application filed January 16, 1919. Serial No. 271,408.

To all whom it may concern:

Be it known that I, THEODORE LIND, a citizen of the United States, residing at Taylorville, in the county of Christian and State 5 of Illinois, have invented a new and useful Foot-Controlled Accelerator, of which the following is a specification.

This invention relates to a foot controlled accelerator for motor vehicles, one of its objects being to provide a novel form of foot rest on which the foot of the driver can be supported comfortably and which with a slight natural movement of the foot will cause the actuation of the accelerating mechanism.

A further object is to provide a foot rest of this character which steadies the foot of the driver and does away with unintentional acceleration such as often occurs when driving over rough ground.

A further object is to provide a foot rest which reduces the wear of a floor and mat of the vehicle and prevents the foot from slipping out of proper position.

A further object is to provide a device of this character which can be easily placed in and removed from the position and which can be adjusted relative to the driver.

With the foregoing and other objects in view, which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

In the accompanying drawings the preferred form of the invention has been shown.

In said drawings:

Figure 1 is a plan view of the device.

Fig. 2 is a section on line 2—2, Fig. 1.

Fig. 3 is a section on line 3—3, Fig. 2.

Referring to the figures by characters of reference 1 designates a rectangular frame provided in its top with an opening 2 and in its bottom with a smaller opening 3. Side openings 4 are provided in the frame for the reception of clamping bolts 5. These screws engage slots 6 formed in the depending portions 7 of attaching plates 8 which are angular as shown. The laterally extending portions of the attaching plates are adapted to rest on and to be secured to the floor of a

motor vehicle and by loosening the bolts 5, the frame 1 can be raised or lowered relative to the floor.

A spindle 9 is mounted for rotation in the openings 2 and 3, the upper portion of the spindle being of greater diameter than the lower portion and being provided with a flange 10 which bears downwardly on the frame 1. The said upper portion of the spindle has an elongated angular socket 11 extending downwardly thereto. A collar 12 is adjustably and detachably mounted on the spindle and bears downwardly on the lower portion of the frame 1. Another collar 13 is detachably and adjustably secured to the spindle 9 below and close to the bottom of the frame 1 and has a radial arm 14 extending therefrom for attachment to a rod which is not shown and which is adapted to be connected to the carbureter of the vehicle.

The foot rest includes a sole plate 15 the right side portion of which is upturned slightly to form a flange 16. The heel plate 17 of the rest is integral with and slightly below the sole plate 15 and is provided along a portion of the back and the left side thereof with an upstanding flange 18.

In using the attachment it is connected to the floor of the motor vehicle and after being properly adjusted and tightened, the foot rest is placed in position by inserting into the socket 11 an angular stem 19 which projects downwardly from the sole plate as shown. It will support the foot comfortably and in a natural position and by turning the foot slightly to the right it will cause the foot rest to move therewith because of the pressure exerted against the flanges 16 and 18. This rotation of the foot rest will be transmitted to the spindle 9 and thence through the arm 14 to the carbureter, thereby to control the same. As the foot rest is adjustable angularly to any desired position it can be arranged to fit the foot comfortably and can be used as a brace for the body and at the same time be turned to the right or to the left to get the necessary adjustment of the carbureter. This adjustment can be very minute and by having the foot rest turn about a substantially vertical axis, there is no danger of actuating the carbureter or accelerator mechanism inadvertently as is often the case where the ordinary foot piece is provided and the machine is traveling.

over a rough piece of ground. The foot rest can be lifted readily out of engagement with the spindle 9, thus to allow placing or removal of the mat of the floor of the vehicle. The flanges 16 and 18 are not very high and, therefore, the foot can be quickly and easily lifted out of engagement with the rest.

What is claimed is:

1. The combination with a spindle mounted for rotation and adjustably supported means constituting a bearing for the spindle, of means operated by the rotation of the spindle for controlling the carbureter, a foot rest, and a stem extending from the foot rest and detachably engaging the spindle.

2. The combination with a spindle having a socket in one end, a bearing for the spindle and means operated by the rotation of the spindle for controlling a carbureter, of a foot rest including a sole plate and a depressed heel plate, a stem projecting from the sole plate and detachably seated in the socket in the spindle, and an upstanding

flange at one side of the sole plate and at the other side of the heel plate.

3. The combination with a frame and an attaching plate adjustably connected to the sides of the frame, of a spindle journaled in the frame and having a socket in its upper end an arm detachably connected to the spindle and revoluble therewith for controlling a carbureter, a sole plate, a heel plate integral therewith and offset downwardly therefrom, upstanding flanges upon one side of the sole plate and the opposite side of the heel plate respectively, and a stem depending from the sole plate and detachably seated in the socket in the spindle.

In testimony that I claim the foregoing as my own, I have hereto affixed my signature in the presence of two witnesses.

THEODORE LIND.
